(57) **CLAIM**

The ornamental design for a kiosk wall mount bracket as shown and described.

DESCRIPTION

FIG. 1 is a top, front, right perspective view of an embodiment of the kiosk wall mount bracket;

FIG. 2 is a front view of the kiosk wall mount bracket of FIG. 1;

FIG. 3 is a rear view of the kiosk wall mount bracket of FIG. 1;

FIG. 4 is a left side view of the kiosk wall mount bracket of FIG. 1;

FIG. 5 is a right side view of the kiosk wall mount bracket of FIG. 1;

FIG. 6 is a top view of the kiosk wall mount bracket of FIG. 1;

FIG. 7 is a bottom view of the kiosk wall mount bracket of FIG. 1;

FIG. 8 is a top, front, right perspective view of another embodiment of the kiosk wall mount bracket;

FIG. 9 is a front view of the kiosk wall mount bracket of FIG. 8;

FIG. 10 is a rear view of the kiosk wall mount bracket of FIG. 8;

FIG. 11 is a left side view of the kiosk wall mount bracket of FIG. 8;

FIG. 12 is a right side view of the kiosk wall mount bracket of FIG. 8;

FIG. 13 is a top view of the kiosk wall mount bracket of FIG. 8; and,

FIG. 14 is a bottom view of the kiosk wall mount bracket of FIG. 8.

The ornamental design which is claimed is shown in solid lines in the drawings. The broken lines of equal length dashes in the drawings are for illustrative purposes and form no part of the claimed design.
